LOCK FOR LAUNDRY WASHER DOORS

Alden B. Battis, Dedham, Mass., assignor to
Henrici Laundry Machinery Company, Boston,
Mass., a corporation of Massachusetts

Application November 16, 1939, Serial No. 304,644

4 Claims. (Cl. 292—146)

This invention relates to an improvement in laundry washers and has as its primary object means for locking the doors of a multi-chamber washer whereby the order in which the doors may be opened and closed is fixed and all the doors may be locked closed by the provision of a single locking unit acting upon one door.

This invention is shown in the drawing and will be described as employed in a dual-chamber washer, but obviously it is not limited thereto since it could be employed in washers having more than two chambers.

In the drawing

Figs. 1, 2 and 3 illustrate in front elevation a dual-chamber washer with the doors in various positions and equipped with such locking means, portions of the washer in Fig. 1 being broken away;

Figs. 4, 5 and 6 are enlarged views of the locking means of the washers within the circles 4, 5 and 6 in Figs. 1, 2 and 3 respectively;

Fig. 7 is a perspective view of a bolt of such locking means; and

Fig. 8 is a cross-sectional view illustrating one way of mounting the bolt and its relation to the elements directly associated therewith.

The dual-chamber washer 10 shown in the drawing includes doors 11 and 12 mounted for raising or lowering in the housing 15 which, as is the usual practice, encloses a rotatable drum (not shown) in which the articles to be washed are carried. The drum is actuated by suitable driving means enclosed within the casing 16 and also includes doors through which access may be had to the interior of the drum. Through suitable means common to this art and not here shown, since they form no part of the present invention, the drum may be brought to rest with the doors therein in register with the doors in the housing.

The doors 11 and 12 are arcuate and the portion of the housing in which they are mounted is similarly formed so that the doors, when raised or lowered, slide in an arc around the housing in suitable guide means. The housing includes an arcuate plate 20 which extends over the adjacent side edges of the doors. That plate is mounted upon an arcuate support between the doors, such support being here shown as comprising a pair of bands 21 and 22. The upper band 22 is separated to provide a pocket 23 in which is supported the bolt 25 of the locking means.

As shown particularly in Fig. 7 the ends of the bolt are rounded and reversely tapered. The

side edges of the doors covered by the plate 20 are notched to receive the ends of the bolt 25. The notch 26 is at the top of the door 11 and the notch 27 is at the bottom of the door 12. The bolt 25 is longer than the width of the supporting bands 21 and 22 and the notches are of such depth that when one end of the bolt is in the notch of one door the other is substantially flush with the other face of the supporting bands (see Figs. 4, 5 and 6).

The locking means functions as follows: When both doors are closed (Figs. 1 and 4), the bolt 25 is in the notch 26 of the door 11. The raising of that door is accordingly prevented, but the door 12 is free to be opened. After the door 12 is fully opened, the notch 27 therein registers with the end of the bolt 25 so that when the door 11 is raised the bolt is shifted into the notch 27 thus locking the door 12 in the open position (Figs. 2 and 5, and Figs. 3 and 6).

Only when the door 11 is fully closed (Figs. 1 and 4) is the notch 26 in register with the bolt 25 so that the door 12 can be closed, and only when the door 12 is fully open is the notch 27 in register with the bolt 25 so that the door 11 can be opened.

It is the universal practice in machines of this type to provide means by which the doors of the housing are locked when the drum is being rotated and thus to prevent injury to the operator. One advantage of this invention is that in a washer so equipped only one door (as here shown the door 12) need be so locked. Various locking means having interrelation with the drum driving means may be employed, one such being indicated on the drawing by the reference numeral 30.

While one embodiment of this invention has been described, and that with reference to its employment in a washer of the dual-chamber type, it will be understood that the invention is not limited thereto, since other embodiments may be made and employed with other types of washers without departing from the spirit and scope of the invention as set forth in the accompanying claims.

I claim:

1. In a laundry washer of the multi-chamber type including a housing provided with a plurality of doors, means for controlling the opening and closing of the doors in a predetermined order whereby one door must be first to be opened and the last to be closed, said means including a bolt mounted between two doors and adapted to engage the adjacent edges of said doors, the

edge of one door having a notch therein which registers with one end of the bolt when the door is closed, and the edge of the other door having a notch therein which registers with the other 5 end of the bolt when the door is open.

2. In a laundry washer of the multi-chamber type including a housing provided with a plurality of doors, means for controlling the opening and closing of the doors in a predetermined order 10 whereby one door must be first to be opened and the last to be closed, said means including a bolt mounted between two doors and laterally movable relative to the adjacent edges of said door, the edge of one door having a notch therein 15 which registers with the bolt when that door is closed, and the edge of the other door having a notch therein which registers with the bolt when that door is opened, the lateral movement of the bolt into a notch in register therewith preventing movement of the door provided with such notch and permitting movement of the other door.

3. In a laundry washer of the multi-chamber type including a cylindrical housing provided 25 with a pair of arcuate doors slidable in parallel, a strap extending over the adjacent edges of both

doors, a bolt below said strap in the space between the doors, said bolt being longer than the distance between the door edges and each of said edges having a notch therein adapted to receive an end of the bolt, whereby the door in 5 the notch of which is received the end of the bolt being held against movement while the other door is freely movable.

4. In a laundry washer of the multi-chamber type including a cylindrical housing provided 10 with a pair of arcuate doors slidable in parallel, a strap extending over the adjacent edges of both doors, a bolt below said strap in the space between the doors, said bolt being longer than the distance between the door edges and each of 15 said edges having a notch therein adapted to receive an end of the bolt, the notch in one door being in register with the bolt when that door is closed and the notch in the other door being in register with the bolt when that door is 20 open, whereby the first-mentioned door is movable only when the second-mentioned door is open and the second-mentioned door is movable only when the first-mentioned door is closed.

ALDEN B. BATTIS. 25
